UNITED STATES PATENT OFFICE

134,903

DESIGN FOR A SEDAN CRUISER

Angus Roy Gross, Baltimore, Md.

Application October 2, 1942, Serial No. 108,399

Term of patent 14 years

To all whom it may concern:

Be it known that I, Angus R. Gross, a citizen of the United States, residing at Baltimore, State of Maryland, have invented a new, original, and ornamental Design for a Sedan Cruiser, of which the following is a specification, reference being had to the accompanying drawings, forming a part thereof.

In the drawings:

Fig. 1 is a side elevational view of a sedan cruiser showing my new design.

Fig. 2 is a horizontal section on the line 2—2, Fig. 1.

Fig. 3 is a perspective view looking forward within the deck house showing the bed in raised position.

Fig. 4 is a perspective view looking aft within the deck house showing the bed in raised position.

Fig. 5 is a perspective view looking sideways into the galley within the deck house.

The cruiser of my design is characterized by the portions shown in full lines in the drawings, and especially the deck house as best shown by the interior views in Figs. 3, 4 and 5.

I claim:

The ornamental design for a sedan cruiser, substantially as shown and described.

ANGUS ROY GROSS.
